Frank J. Basser

ATTORNEY.

UNITED STATES PATENT OFFICE.

FRANK S. SNYDER, OF POUGHKEEPSIE, NEW YORK, ASSIGNOR TO THE DE LAVAL
SEPARATOR COMPANY, OF NEW YORK, N. Y., A CORPORATION OF NEW JERSEY.

CENTRIFUGAL SEPARATOR.

1,283,343.

Specification of Letters Patent. Patented Oct. 29, 1918.

Application filed August 31, 1917. Serial No. 189,074.

To all whom it may concern:

Be it known that I, FRANK S. SNYDER, a citizen of the United States, residing at Poughkeepsie, county of Dutchess, and State 5 of New York, have invented a new and useful Improvement in Centrifugal Separators, of which the following is a full, clear, and exact description, reference being had to the accompanying drawings, which form a 10 part of this specification.

The object of my invention is to provide a centrifugal machine for clarifying gasolene in a continuous manner—more specifically, for so separating gasolene from a mixture or emulsion of the same with water, soap 15 and dirt. The invention is especially adapted for use in carrying on the process described by Meredith Leitch in his patent application Serial No. 147,333, filed February 20 8, 1917.

A preferred embodiment of the invention is illustrated in the accompanying drawings, in which—

Figures 1 and 2 show samples respectively 25 of gravity and centrifugally treated gasolene mixtures. Fig. 3 shows a side elevation, in partial vertical section, of a clarifier or separator embodying my invention.

It is impossible, by gravity, to effect a 30 clear and complete separation of the gasolene. Fig. 1 graphically represents a sample of dirty gasolene that has been allowed to separate by standing for forty-eight hours. The upper layer of the sample consists of 35 gasolene; below this is a deep layer, 12% of the total, consisting of an emulsion of gasolene, soap, dirt and water; the bottom layer consists of water. Fig. 2 represents a 40 sample of the same dirty gasolene that has been centrifuged between one and two minutes. The upper layer of the sample consists of gasolene; below this is a small zone of soap carrying light dirt; the next zone consists of water; the lower layer is heavy 45 dirt.

Examination of the centrifuged sample shows that the mixture consists of 43½% of gasolene and 13½% of water, dirt, soap, etc. By the centrifugal process all of this gasolene is recovered at once. By the gravity 50 process 6½% is lost even after setting forty-eight hours.

However, the ordinary centrifugal separator, such, for example, as any of the various types intended for the separation of milk and cream, are not effective, when op-

erated continuously, to produce the perfect result obtained, as illustrated in Fig. 2, in the treatment of a definite small quantity of dirty gasolene. Either the gasolene will 60 be imperfectly cleaned or some of the gasolene will be lost with the dirt and water. In the continuous operation of the separator which I have invented, however, the results are approximately perfect, and comparable 65 with those diagrammed in Fig. 2. Clean gasolene only is discharged from one opening and the other constituents free from gasolene from another opening.

When the centrifugal bowl is opened the 70 material in the bowl is found to be in concentric zones corresponding to the layers in the centrifuged sample. Next to the outside shell is a thin layer of heavy dirt, then 75 a layer of water. Inside that is a layer of soap and light dirt and around the center clean gasolene. In a centrifugal bowl much of the easily separated gasolene escapes quickly, as does most of the water. In order 80 to extract the last traces of gasolene from it, the soap is held in the bowl for a long time. This results in a soap zone much wider in proportion than that shown in the centrifuged sample.

The mixture to be treated may change 85 from much dirt and water with a little gasolene, when beginning to draw from the bottom of a tank, to nearly all gasolene and soap with a little water emulsed with it, when taking off the last from a tank. Under 90 no conditions must gasolene escape with the water, nor must water, dirt or soap be discharged with the gasolene. It is thus seen that the problem is altogether different from 95 that of a milk separator that has a nearly uniform mixture to separate and is never expected to make a complete separation of the butter fat from the skim milk.

I have found that, to obtain the cleanest 100 gasolene, the liquid should be delivered to the separating disks near their peripheries and travel, between the disks, inward toward the center, leaving all dirt, water, soap, etc., behind it.

In order to prevent escape of gasolene with 105 the water, the top disk, dividing the water and soap-escape passage from the rest of the bowl, should be made of the maximum diameter possible and the relative radii of the water and gasolene discharge openings 110 should be such that centrifugal force acting on the water outside of and above the top

disk will balance the centrifugal force acting on the gasoline inside and below the top disk and maintain a water seal around the edge of the top disk.

5. In other words, with the amount of desired water seal specified the discharge openings for light and heavy liquids may be determined by the following equation:

$$GL(R^2 - rL^2) = GH(R^2 - rH^2)$$

10 in which—

GL =specific gravity of light liquid.

GH =specific gravity of heavy liquid.

15 rL =radius of the discharge for light liquid.

rH =radius of the discharge for heavy liquid.

20 R =radius to the inside of the water seal, which must be not more than, nor less than eight-tenths of, the radius of the bottom of the discharge disk.

Thus, if the specific gravity of the heavy liquid be assumed to be 1. and of the light liquid .9, the radii of the discharge for light liquid, of the discharge for heavy liquid and to the inside of the water seal would be respectively 3, 5 and 13, and the radius of the bottom of the discharge disk would be between 13 and 16.

25 30 Where it is desired to separate gasoline from dirt, water and soap, a separator constructed in accordance with the proportions of the annexed drawings will satisfy the requirements and respond to the above formula.

35 In order to obtain high capacity, the liquid entering the bowl must be brought up to the speed of the bowl quickly and at no time during its passage to the periphery be allowed to lag behind the bowl nor during its passage

40 inward from the periphery be allowed to run ahead of the bowl. These are accomplished by having wings at various parts of the bowl to accelerate or retard, as may be necessary, the rotation of the liquid.

45 I have also found it necessary, in order to obtain perfectly clean gasoline, to provide passages at the inner edge of the soap zone for a free flow of soap from those inter-disk spaces where the inward flow of liquid is so

50 rapid as to interfere with the outward flow of soap, to those inter-disk spaces where the flow is less rapid.

In order to obtain the best results, the radii of the discharge openings for the light

55 and heavy liquids should be such that the centrifugal force acting on the lighter liquid, below the discharge disk, and that acting on the heavier liquid, above the disk, will balance at a radius slightly less than the extreme radius of the discharge disk.

60 Referring to Fig. 3, the bowl shell a is carried on and revolved by a shaft b , which enters a socket in the bowl nave c . Around the bowl nave is a propelling screw d , and

65 fitting closely around that is a disk carrier e ,

an upward extension of which forms a central receiving chamber f . Across the bottom of the disk carrier e are several passages g leading from the central opening around the bottom of the screw d to the periphery of the 70 carrier.

Attached to disk carrier e is a petticoat h . Leading from a point adjacent to each passage in the disk carrier to the periphery of the petticoat is a driving wing i . Above the 75 petticoat are a number of separating disks j , each having a large hole k at approximately the inner edge of the soap zone. Secured to the bowl shell are several wings m extending inward to the edges of the separating disks j . 80 Near the top of the bowl is the discharge disk n , preferably made as large as can be passed through the internal flange at the top of the bowl shell. This disk has a neck o of comparatively small diameter extending 85 above the bowl top and has on its upper side several wings p that fit closely against the bowl top r . The bowl top is secured to the shell by the usual nut s and has the usual discharge opening t at the center. 90

In operation, the dirty gasoline is supplied through a feed tube, not shown, and enters the central receiving chamber f . The propelling screw d catches it and forces it downward to the bottom of the bowl and into 95 the passages g . As the gasoline escapes from these passages, it is caught by the wings i and afterward by the wings m and forced to continue rotating at the same speed as the bowl. Between the wings m , the 100 heavy dirt is thrown out against the shell and part of the water is immediately thrown out. Part of the gasoline passes in very quickly between the lower disks to the center of the bowl. The emulsion of gasoline, 105 soap and water enters between the disks and is there separated. As the soap accumulates it is forced out from between the disks and displaces the water that at first fills the spaces between the wings m until the soap 110 zone finally reaches the edge of the discharge disk n , and escapes around it.

This soap, with the water, flows upward and inward between the discharge disk n , and the bowl top r , and escapes at t . The 115 wings p , on top of the discharge n , prevent the escaping water and soap running faster than the bowl and developing a great centrifugal force that would resist the flow. The gasoline flows inward between the disks j , 120 leaving all dirt, soap and water behind it, and after flowing upward, inside the neck o of the discharge disk, escapes at u . The holes k through the disk j provide passages for the distribution and equalization between 125 disks of the soap and gasoline.

Having now fully described my invention, what I desire to claim and protect by Letters Patent is:

1. In a centrifugal separator for liquids 130

having a heavy slimy constituent, the combination, with a rotatable bowl, of a liner in the bowl adapted to divide the liquid into thin layers and spaced a substantial distance 5 from the bowl wall to afford an open annular space, a central receiving chamber and passages therefrom to the outer part of the separating chamber of the bowl, a discharge disk above the liner the outer part of which over-
10 hangs the liner and is spaced a relatively short distance from the bowl wall, means affording an escape opening for the lighter constituent from below the discharge disk, means providing an escape opening from 15 above the discharge disk for the heavier constituent, and a wing above the discharge disk extending inward as far as the discharge for the heavy liquid.
2. In a centrifugal separator for liquids 20 having a heavy slimy constituent, the combination, with a rotatable bowl, of a liner in the bowl adapted to divide the liquid into thin layers and spaced a substantial distance from the bowl wall to afford an open annular space, a central receiving chamber and 25 passages therefrom to the outer part of the separating chamber of the bowl, a discharge disk above the liner the outer part of which overhangs the liner and is spaced a relatively 30 short distance from the bowl wall, means

affording an escape opening for the lighter constituent from below the discharge disk, means providing an escape opening from above the discharge disk for the heavier constituent, and wings between the periphery 35 of the liner and the bowl wall and between the discharge disk and the bowl cover, the latter wing extending inward as far as the discharge for the heavier constituent.

3. In a centrifugal separator for liquids 40 having a heavy slimy constituent, the combination, with a rotatable bowl, of a central feed tube, a liner consisting of a set of superimposed frusto-conical disks occupying part of the separating space in the bowl, said 45 disks having equalizing orifices between their inner and outer edges, a frusto-conical petticoat beneath the liner, an imperforate frusto-conical discharge disk above the liner, and wings below the petticoat, between the 50 periphery of the liner and the bowl wall, and above the discharge disk, there being a discharge orifice for the heavier constituent 55 above the discharge disk near the inner part of the same.

In testimony of which invention, I have hereunto set my hand, at Poughkeepsie, N. Y., on this 24th day of August, 1917.

FRANK S. SNYDER.
